GUARD FOR DERAILLEUR BICYCLE GEARS

Carl A. Swenson, 615 N. Berlyn Ave., Ontario, Calif.

Filed Dec. 11, 1963, Ser. No. 77,759

Term of patent 14 years

(Cl. D90—5)

FIG. 1 is a side perspective view of a guard for derailleur bicycle gears showing my new design;

FIG. 2 is a side elevational view taken from the same side as shown in FIG. 1;

FIG. 3 is an elevational view thereof as seen from the right of FIG. 2;

FIG. 4 is a top plan view; and

FIG. 5 is a sectional view taken on the line 5—5 of FIG. 3.

In the drawing figures the characteristic features of my design are shown by means of full lines.

I claim:

The ornamental design for a guard for derailleur bicycle gears, as shown and described.
